UNITED STATES PATENT OFFICE.

CHARLES A. LINDSTRÖM, OF ALLEGHENY, PENNSYLVANIA, ASSIGNOR TO PRERESSED STEEL CAR COMPANY, OF PITTSBURG, PENNSYLVANIA, A CORPORATION OF NEW JERSEY.

TANK-VALVE.

No. 902,748.

Specification of Letters Patent.

Patented Nov. 3, 1908.

Application filed May 31, 1904. Serial No. 210,402.

To all whom it may concern:

Be it known that I, CHARLES A. LINDSTRÖM, of Allegheny, Allegheny county, Pennsylvania, have invented a new and useful Tank-Valve, of which the following is a full, clear, and exact description, reference being had to the accompanying drawings, forming part of this specification, in which—

Figure 1 is a vertical central section of a valve constructed in accordance with my invention; Fig. 2 is a horizontal section on the line II—II of Fig. 1; Fig. 3 is a sectional plan view on the line III—III of Fig. 1 illustrating the preferred manner of connecting the valve-stem to the valve; Fig. 4 is a detail view of the valve-stem; Fig. 5 is a partial vertical section and side elevation of a tank for tank-cars fitted with my valve; and Figs. 6 and 7 are respectively a plan and side view 20 of the means for lifting the valve-stem.

The purpose of my invention is to improve the construction of tank-valves such as used for tank-cars in order to make it possible to empty the entire contents of the car when desired, and to provide for the partial discharge of the contents.

A valve constructed in accordance with my invention possesses advantages over those heretofore used in respect of a simple and 30 cheaper construction and a better provision against leaks.

In the drawing 2 represents the valve-casing or housing which is riveted or otherwise secured as at 3 to the bottom of the tank 35 4, and has at its upper end a seat 5 for the valve 6 which is swiveled on a vertical stem 7. This stem preferably fits in a socket 8 at the top of the valve, and has a peripheral groove 9, enabling it to be connected with the socket 40 by a U-shaped cotter 10, which is inserted in the socket and fits within the groove 9 as shown in Figs. 1 and 3. The valve 6 is preferably formed with radial wings 6' between which is a removable set-screw 11 which projects through the casing into the space between two of the wings and thus enables the valve to move vertically, but limits its turning motion. The valve has a downwardly 45 projecting sleeve 12 having a threaded portion at its lower end in which fits the threaded stem 13 of a cap 14 which is adapted to fit within the lower end of the casing 2 and has a flange 15 bearing against a gasket or packing ring 16 at the end of the casing. The cap 50 has a squared portion 17 for the application

of a wrench by which it may be turned, and when so turned the stem 13 can be screwed into the sleeve 12, and the cap 14 thus brought towards the valve 6, with the effect of drawing the valve to its seat 5 and of seating the cap against the gasket 16, thus closing the casing at both ends.

When it is desired to open the valve to permit the partial discharge of the contents of the tank, the cap 14 may be turned so as to unscrew its stem partially from the socket, thus freeing the valve 6, which can then be raised and lowered vertically by means of its stem 7. By removing the cap 14 the valve 6 can be raised to cause the entire discharge 70 of the contents of the tank.

A part of my present invention consists in making the stem 13 a part of the cap 14, and the threaded sleeve 12 a part of the valve 6. This affords a cheaper and stronger construction than if the stem were part of the valve and were screw-threaded into the cap, for the housing 2 must be of considerable length in order to extend below the center sills of the car to which it is applied, and as the valve 80 proper is frequently made of brass, while the cap is made of gray or malleable iron, I effect a considerable saving by lessening the amount of material of the valve.

As the stem 7 is swiveled to the valve, it 85 enables me to lift the valve either with a direct vertical motion or by a vertical motion produced by rotation of the stem as desired.

I prefer to employ the lifting device shown in Figs. 5, 6 and 7 in which the stem at its upper end has a handle 18 within the tank which bears upon an inclined arc 19 forming part of a supporting bracket 20. By rotating the handle 15 along the arc in the direction of the arrow in Fig. 6 the stem and valve 95 are raised after the cap has been loosened or removed from the valve. At the end of the inclined arc 19 is a recess and retaining notch 21 for retaining the handle at the end of its motion, thus keeping the valve open. The 100 swiveled connection of the stem with the socket is also of advantage because it enables the valve to be rotated by the cap 14 within the limits of the loose motion afforded by the stop or set screw 11.

I claim:

1. In a discharge valve for tank cars, the combination with a tubular casing having a valve seat at one end, a valve located in said casing shaped to fit said seat, short relatively 110

- to said casing and formed with internal screw-threading in its lower end and a cap for the lower end of said casing having an elongated stem threaded to fit the lower end 5 of said valve.
2. In a discharge valve for tank cars, the combination with a tubular casing having a valve seat at one end, a valve located in said casing shaped to fit said seat, short relatively 10 to said casing and formed with internal screw-threading in its lower end, and a cap for the lower end of said casing having a tapered elongated stem threaded to fit the lower end of said valve.
- 15 3. In a discharge valve for tank cars, a tubular casing; a valve in said casing, short relatively thereto and having narrow elongated radial wings, a set screw in said casing projecting into a space between a pair of said 20 wings to permit a limited rotary movement of said valve, a valve stem, stem elevating cam means at the upper end of said stem, a peripheral groove in said stem at its lower end, a socket in the valve, a U-shaped cotter

fitting in said groove and socket and a female 25 thread formed in the lower end of said valve in combination with a cap for the lower end of said casing having a tapered elongated stem threaded to fit the female thread in said valve.

4. In a discharge valve for tank cars, the combination with a tubular casing having a valve seat in one end, a valve located in said 30 casing, short relatively thereto, shaped to fit said seat and provided with a screw threaded lower portion, a cap for the lower end of said 35 casing having a stem threaded to fit the threading on the lower portion of said valve, of a vertically reciprocating valve stem, a lever for elevating said stem and a cam over 40 which said lever is moved to elevate said stem.

In testimony whereof, I have hereunto set my hand.

CHARLES A. LINDSTRÖM.
